UNITED STATES PATENT OFFICE.

EMILE J. GUAY, OF SWAMPSMOTT, MASSACHUSETTS, ASSIGNOR TO GENERAL ELECTRIC COMPANY, A CORPORATION OF NEW YORK.

TESTING CUT-OUT FOR ARC-LAMPS.

1,156,526.

Specification of Letters Patent.

Patented Oct. 12, 1915.

Continuation in part of application Serial No. 544,572, filed February 18, 1910. This application filed July 20, 1911. Serial No. 639,513.

To all whom it may concern:

Be it known that I, EMILE J. GUAY, a citizen of the United States, residing at Swampscott, in the county of Essex and State of Massachusetts, have invented certain new and useful Improvements in Testing Cut-Outs for Arc-Lamps, of which the following is a specification.

This application is in part a continuation 10 of my prior application, Serial No. 544,572, filed February 18, 1910, for testing cutouts for arc lamps.

The invention relates to electric luminous arc lamps arranged in a circuit that is periodically broken and again established at the central station to cause the feeding of the electrodes, and its object is to provide a closed circuit through the lamp for testing purposes when the lamp is out of service.

20 In lamps of the luminous arc type, a crust of metallic oxide is liable to form on the tips of the electrodes when they cool, after the lamp is extinguished. These crusts are of high resistance, so that the low voltage testing current does not readily flow through them, and, if this happens, it becomes difficult for the testing operator at the power station to distinguish between an open line and a high resistance electrode tip. My invention effectually eliminates this trouble by automatically closing a resistance shunt path across the lamp terminals immediately after the line current is switched off the lamp, said shunt affording a path for the 30 testing current. At the same time, I provide a second low resistance path across the lamp terminals, and means for making this shunt path of a comparatively low resistance when a predetermined voltage is impressed across the same. In the embodiment here illustrated, this means comprises a spark gap so arranged as to short circuit the first shunt path and the lamp itself in case a non-conducting layer is formed upon either or both of the electrodes, which the voltage across the electrodes at the moment they are separated is unable to break down, while it is able to break down the short circuiting spark gap, which short circuit then 40 persists until the circuit therethrough is broken, usually by an automatic circuit breaker at the central station.

The accompanying drawing is a diagram

of the circuits of a luminous arc lamp embodying my invention.

55 The lamp shown comprises two lower electrodes 1, 2 inclined toward each other with their upper ends abutting. The mechanism for feeding these two electrodes upward as they burn away is not shown, being now well known in lamps of this type. In the lamp shown there is a single upper electrode 3. The lifting magnet 4 has its coils in series with the electrodes, its movable core 5 being pivotally attached to a lever 6 which by means of a link 7 actuates the clutch 8 co-operating with the upper electrode, which is vertically movable for the purpose of drawing the arc. The clutch co-operates with the tripping platform 9 of the lamp, and the arc is practically stationary and of fixed length.

70 Operatively connected with the lever 6 is a switch, preferably comprising a lever 10 which carries an insulated contact 11 co-operating with a stationary contact 12; the two contacts being located in a shunt across the arc in series with the lifting magnet. A resistance coil 13 is included in this shunt. When the arc is struck the contacts are 75 separated, but, when the line current is switched off and the upper electrode drops, the contacts close together and the shunt circuit is completed.

75 A spark gap, including stationary contacts 14, 15 and a movable contact 18, is connected across the lamp. The movable contact 18 is carried by the armature 17 which co-operates with a coil 16 included in series with the spark gap. The distance between 80 the contacts 14 and 15 is made so short that an arc would cross the gap when a predetermined voltage occurs across the terminals of the lamp.

85 The cycle of operations of this device is 90 as follows: When the current is off, the electrodes are together, the armature of the cut-out magnet and that of the lifting magnet are at rest, and the contacts 11, 12 are closed, thereby putting the resistance and the electrodes in multiple and in series with the lifting magnet across the lamp terminals; the contacts 15 and 18 are separated a distance equal to or greater than the distance between contacts 14 and 15. When the current is thrown on and there is no insulating

slag on the electrodes, the current passes through the lifting magnet which opens the contacts 11, 12 and draws the electrodes apart and establishes the arc. But if a non-conducting layer or crust has formed upon the luminous electrodes, and current is turned on the circuit, the magnet 4 is energized through the shunt circuit which includes the contacts 11 and 12 and resistance 5. The armature 5 is lifted and the parts are so designed that the contacts 11 and 12 are separated prior to the separation of the electrodes, and the voltage across the two electrodes is ordinarily sufficient to break 10 down a slight non-conducting layer that may have formed on the electrode tips. The upper electrode is then lifted and an arc is formed between the electrodes. In case the non-conducting layer on the electrodes is too heavy, the arc is not established, and, in this case, the voltage across the spark gap becomes sufficiently high to cause a spark or arc to bridge the gap and thus energize the coil 16 and attract the 15 armature 17. If this occurs, the movable contact 18 will be brought into engagement with the contact 15. The armature 5 and the parts connected thereto will immediately resume their original positions, the contact 20 11 engaging the contact 12 and the upper electrode 3 falling back upon the lower electrode with sufficient force to ordinarily break the crust or non-conducting layer that may have formed upon the electrode 25 tips. The lamp then remains in this condition, that is, with the upper electrode in engagement with the lower electrode and the contact 18 in engagement with the contact 15, the lamp remaining short-circuited until 30 the main circuit is, for the purpose of feeding, broken by automatic mechanism at the central station. When the main circuit is thus broken, the coil 16 will be deenergized and the spark gap opened. Immediately 35 after this, the main circuit is again closed and the cycle of operation will be repeated as above described.

From the foregoing description, it will be seen that the testing contacts 11, 12, in conjunction with the shunt gap contacts 14, 15 and 18, operate to cause the upper electrode to give a hammer blow to the lower electrode for the purpose of breaking down any insulating layer that may have formed on the electrode tips and then short circuit the lamp, until, at the central station, the line circuit is again opened and made for the purpose of feeding. In addition to this, the testing contacts always close the shunt, which includes the magnet coil 4 and resistance 13, for testing purposes, when no operating current is on the line.

What I claim as new, and desire to secure by Letters Patent of the United States, is:—

66 1. In an arc lamp, a pair of electrodes,

means for establishing the arc, a normally closed shunt path across the electrodes, means for opening said shunt path by the arc establishing means, a normally high resistance shunt path across the terminals of the lamp, and means for making this shunt of comparatively low resistance when a predetermined voltage is impressed across the same.

2. In an arc lamp, a pair of electrodes, means comprising a magnet and its armature for striking the arc, a shunt path across the arc including said magnet, means responsive to the movement of the armature for opening said shunt path, a normally high resistance shunt path across the terminals of the lamp, and means for making this shunt of comparatively low resistance when a predetermined voltage is impressed across the same.

3. In an arc lamp, a pair of electrodes between which the arc is maintained and upon one or both of which a non-conductive layer may be formed, means for establishing the arc, a testing shunt path connected across the arc, means for open circuiting said shunt path by the arc establishing means, a normally high resistance shunt path across the terminals of the lamp, and means for making this shunt path of comparatively low resistance when the arc establishing means is actuated and the arc fails to start, thereby impressing a relatively high voltage across said second shunt path.

4. In an arc lamp, a pair of electrodes between which the arc is maintained and upon one or both of which a non-conducting layer may be formed, means for establishing the arc including a magnet and its armature, a shunt path connected across said electrodes in series with the magnet, means responsive to the movement of said armature for open circuiting said shunt path, and a second shunt path of lower resistance connected across the lamp comprising a two-branch air gap, a low resistance magnet in series therewith, and means for closing one air gap branch by the said low resistance magnet.

5. In an arc lamp, a pair of co-operating electrodes, means comprising a magnet for separating the electrodes to establish the arc, a shunt path connected across the electrodes comprising a resistance and a pair of contacts one of which is movable in response to the movement of the armature of said magnet and adjusted to open the shunt path of said contacts prior to the separation of the electrodes, a high resistance shunt path connected across the terminals of the lamp, and means for making this shunt path of comparatively low resistance when a predetermined voltage is impressed across the same.

6. In an arc lamp, a pair of electrodes between which the arc is maintained and upon one or both of which a non-conducting layer may be formed, means for establishing the arc including a magnet and its armature, a shunt path connected across said electrodes in series with the magnet, means responsive to the movement of said armature for open-circuiting said shunt path prior to the establishment of the arc, and a second shunt path of lower resistance con-
- nected across the lamp comprising a two branch air gap, a low resistance magnet in series therewith, and means for closing one air gap branch by the said low resistance magnet.
- In witness whereof, I have hereunto set my hand this seventeenth day of July, 1911.
- EMILE J. GUAY.
